UNITED STATES PATENT OFFICE

THOMAS F. LAMB, OF MANSFIELD, OHIO

MEANS FOR TRANSFERRING GLASSWARE

Application filed May 14, 1927, Serial No. 191,303. Renewed May 28, 1929.

The object of this invention is to provide an improved and simplified means for transferring glass ware, more particularly bottles from the molds to a belt for conveyance to a leer or other point for treatment or otherwise.

The invention is embodied in the example herein shown and described, the features of novelty being finally claimed.

10 In the accompanying drawings—

Figure 1 is a view in elevation of my invention showing the transfer device gripping a bottle in an opened mold.

Fig. 2 is a top plan view of the same.

15 Fig. 3 is a detail illustrating the gripper actuator.

In the views 5 designates the base in which is secured a column 6. On the column 6 is a loose sleeve 7 having at its upper portion a head 8 provided with a cam 9 on its upper face. On the upper portion of the column 6 is another loose sleeve 10 having a head 11 facing the head 8 and provided with a cam 12 cooperating with the cam 9. Around the column 6 between the heads is a loose piece of coil spring 4 to establish friction between the heads either when closed or separated. Secured rigidly to and extending horizontally from the sleeve 10 is an arm 13 riveted at 14

20 near the middle of which is an upstanding arm 15. Pivotaly connected at 16 to the upper end of the arm 15 is a lever 17 the inner end of which engages the groove 18 of a collar 19 fastened by means of a set screw 25

20 to the upper end of the post 6, so that when the sleeve 10 and horizontal bar are raised or lowered the lever 17 is swung up or down with the collar 19 as a fulcrum. The arm 17 is a lever of the third class, its outer end having pivoted to it at 21 and 22 a pair of divergently bent arms 23 and 24 carrying at their lower ends jaws 25 and 26 adapted to grip the neck of a bottle such as shown at 27 Fig. 1. Each of the arms 23 and 24

40 is held and guided in its movement between a pair of pins 28 and 29 in the horizontal arm 13 so that when the lever 17 is swung upward at its outer end with respect to the arm 13 the jaws are closed toward each other to grasp the neck of a bottle; and conversely

when said arm 13 is swung downward the jaws are separated to release the bottle. The members 30 are merely a pair of guide arms secured to the horizontal arm 13 to keep steady the frame constituting the transfer 55 structure proper. Projecting from the lower end of the sleeve 7 is a rigid arm 31 having pivotally attached thereto at a suitable hole 32 therein a rod 33 adapted to be reciprocated by any suitable power and therefore to swing 60 the transfer frame and otherwise operate the same by means of the cams as hereinafter described. The swing of the transfer frame is limited in both directions (determined by the bottle gripping and bottle releasing points) 65 by means of stops 34 and 35 mounted on a bracket 36 on a standard 37, the latter secured at its lower end to the base 5. Each of said stops can be made adjustable by slotting its attaching foot as best illustrated 70 at the stop 35 and securing it in the desired position on the bracket 36 by means of set screw 38.

The operation of the means thus far described is this: When the transfer frame is 75 to take a bottle from the opened mold, it being remembered that the head 11 is down on the head 8, said transfer frame is swung by the operation of the arm 32 toward the stop 34, said stop arresting said frame whereupon 80 continued pressure of the arm 32 in the same direction causes the cam 9 to act on the cam 12 to raise the head 11 thereby closing the jaws on the neck of the bottle 27, the latter being shown in the position it occupies when 85 the parts of the mold at 50 are opened to permit the removal of the bottle. To release the bottle the transfer frame is swung in the opposite direction to the stop 35, said stop arresting said frame with the bottle above the 90 point where it is to be deposited, a continued swing of the head 8 fetches the cam 9 from under the cam 12 thereby permitting the head 11 to descend toward the head 8 and the separation of the bottle grasping 95 jaws. To limit the oscillation of the heads with reference to each other, and therefore to prevent the cams 9 and 12 from getting out of proper operating relation to each other the upper portion of the sleeve 10 is cut away 100

as at 51 and the column 6 provided with a stop 52 to abut against the sleeve at opposite sides of said cut-away portion.

39 designates a circular table onto which the bottles are deposited, said table being supported by a tube 39^a around a stationary post 45, said table having means for intermittently rotating it in one direction, including a loose sleeve 40^a carrying a pawl 40 actuated by a link 41 connecting it with the arm 31 so that, when the transfer frame is swung toward the bottle-taking position, said pawl engages one tooth 42 of a circular series of them on the lower side of the table to effect a partial rotation of the table. 44 designates a spring actuated pawl pivoted on a bracket adapted to engage another tooth 42 after the table has been turned through an arc to prevent retrograde movement of the table when the pawl 40 is drawn to take a fresh tooth upon the movement of the arm 31 to swing the transfer frame to bottle releasing position. The bottle releasing position is over the outer margin of the table and the bottle is there deposited in upright position as indicated in broken lines Fig. 2. Mounted on a stationary post 45 extending up through an orifice in the center of the table 39 is a stationary bracket 46 on which is mounted a stationary deflecting plate 47 adapted to shunt the moving bottle off the table onto an ordinary belt 48, said belt adapted to carry the bottle to a leer. A transferred bottle is indicated at 27 on said belt in Fig. 2.

35 The forms of the parts can be changed and parts omitted without departing from the gist of the invention as claimed.

What I claim is:

1. In means for transferring glass ware from a mold, a vertical column, a sleeve sliding vertically on said column, an arm extending from said sleeve, a lever connected with said arm and having one end fulcrumed on the column, a pair of jaw arms connected with said lever, and means for causing the opening and closing of said jaw arms by movement of said sliding sleeve.

2. In means for transferring glass ware from a mold, a vertical column, a frame on said column including a sleeve sliding vertically on said column, an arm extending from said sleeve, a lever connected with said arm and having one end fulcrumed on the column, a pair of jaw arms connected with said lever, means for causing the opening and closing of said jaw arms by movement of said sliding sleeve, means for swinging said frame, stops for limiting the swinging movement of said frame and means to cause respectively the opening and closing of the jaw arms at the opposite limits of the swinging movement of the frame.

3. In means for transferring glass ware from a mold, a vertical column, a frame on said column including a sleeve sliding verti-

cally on said column, an arm extending from said sleeve, a lever connected with said arm and having one end fulcrumed on the column, a pair of jaw arms pivotally connected with said lever, means for swinging said frame, including a second sleeve on said column, stops for limiting the swinging movement of said frame and means including a cam between said sleeves for actuating the first mentioned sleeve to cause respectively the opening and closing of the jaw arms at opposite limits of the swinging movement of the frame.

4. In means for transferring glass ware from a mold, a vertical column, a frame on said column including a sleeve sliding vertically on said column, an arm extending from said sleeve, a lever connected with said arm and having one end fulcrumed on the column, a pair of jaw arms pivotally connected with said lever, means for swinging said frame, including a second sleeve on said column, resilient frictional means between the sleeves, stops for limiting the swinging movement of said frame and means including a cam between said sleeves for actuating the first mentioned sleeve to cause respectively the opening and closing of the jaw arms at opposite limits of the swinging movement of the frame.

5. In means for transferring glass ware from a mold, a vertical column, a frame on said column including a sleeve sliding vertically on said column, an arm extending from said sleeve, a lever connected with said arm and having one end fulcrumed on the column, a pair of jaw arms pivotally connected with said lever, means for swinging said frame, including a second sleeve on said column, stops for limiting the swinging movement of said frame and means including a cam between said sleeve for actuating the first mentioned sleeve to cause respectively the opening and closing of the jaw arms at opposite limits of the swinging movement of the frame, and means for limiting the rotary movement of said second mentioned sleeve in respect of the first mentioned sleeve.

6. Means for transferring glass ware from a mold including a vertical column, a sleeve sliding vertically on said column, an arm extending from said sleeve, a lever connected with said arm and having one end fulcrumed on the column, a pair of jaw arms connected with the other end of said lever and having their movements for opening and closing controlled by the raising and lowering of the first mentioned arm.

7. Means for transferring glass ware from a mold including a vertical column, a sleeve having a head loosely turning on said column, a second sleeve having a head loosely turning on said column and movable vertically thereon, interengaging cams on said heads, a rigid arm extending from said second named sleeve, a lever connected at one end with the rigid

5 arm and having its other end fulcrumed on the column, a pair of jaw arms connected with the other end of said lever and having their movements for opening and closing controlled by the raising and lowering of the rigid arm.

8. Means for transferring glass ware from a mold including a vertical column, a sleeve having a head loosely turning on said column, 10 a second sleeve having a head loosely turning on said column and movable vertically thereon, interengaging cams on said heads, a rigid arm extending from said second named sleeve, a lever connected at one end with the rigid arm and having its other end fulcrumed on the column, a pair of jaw arms connected with the other end of said lever and having their movements for opening and closing controlled by the raising and lowering of the 15 rigid arm, means for swinging said frame, and stops for limiting the swinging movements thereof in opposite directions, said interengaging cams adapted to cause the raising of said rigid arm and permit the lowering 20 thereof at said stops.
